Primary Examiner — John A Voytek(74) *Attorney, Agent, or Firm* — Sterne, Kessler,
Goldstein & Fox P.L.L.C.(57) **CLAIM**

The ornamental design for a tire, as shown and described.

DESCRIPTION

FIG. 1 is a front perspective view of a tire showing the claimed design;

FIG. 2 is a front view thereof;

FIG. 3 is a rear view thereof;

FIG. 4 is a top plan view thereof, the bottom plan view being the same;

FIG. 5 is a right side view thereof;

FIG. 6 is a left side view thereof;

FIG. 7 is an enlarged view taken along line 7-7 in FIG. 1;
FIG. 8 is an enlarged view of the portion 8-8 in FIG. 2; and,
FIG. 9 is a cross-sectional view taken along line 9-9 in FIG.
8.In the drawings, the broken lines show portions of the tire
that form no part of the claimed design.**1 Claim, 9 Drawing Sheets**FIG. 1
